DESIGN FOR A TRAY

Jean O. Reinecke and James F. Barnes, Chicago,
Ill., assignors to McGraw Electric Company,
Chicago, Ill., a corporation of Delaware

Application August 15, 1938, Serial No. 79,353

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Tray, of which the following is a specification, reference being had to the accompanying drawing, forming part thereof, in which

Fig. 1 is a top plan view of a tray showing our new design,

Fig. 2 is a side elevational view thereof,
Fig. 3 is a fragmentary sectional view there-through taken on the line 3—3 of Fig. 1,

Fig. 4 is an end elevational view thereof, and

Fig. 5 is a fragmentary sectional view there-through taken on the line 5—5 of Fig. 1.

We claim:

The ornamental design for a tray, as shown and described.

JEAN O. REINECKE.
